CLAIM

The ornamental design for an article holding bucket skirt or the like, as shown and described.

DESCRIPTION

FIG. 1 is a front perspective view of an article holding bucket skirt or the like showing my new design;
FIG. 2 is a left side perspective view thereof;
FIG. 3 is a rear perspective view thereof;
FIG. 4 is a right side perspective view thereof; and
FIG. 5 is a top plan view thereof, the interior thereof being substantially plain and unornamented.

FIG. 1

FIG. 2

FIG. 3

FIG. 4

FIG. 5
